UNITED STATES PATENT OFFICE.

THOMAS B. CLARK, OF HONESDALE, PENNSYLVANIA.

DESIGN FOR A CUT-GLASS VESSEL.

SPECIFICATION forming part of Design No. 32,150, dated January 30, 1900.

Application filed December 30, 1899. Serial No. 742,175. Term of patent 3½ years.

To all whom it may concern:

Be it known that I, THOMAS B. CLARK, a citizen of the United States, and a resident of Honesdale, in the county of Wayne and State 5 of Pennsylvania, have invented and produced a new and original Design for a Cut-Glass Vessel, of which the following is a full, clear, and exact description.

Reference is to be had to the accompanying 10 drawings, forming a part of this specification, in which similar characters of reference indicate corresponding parts in both the views.

Figure 1 is an inverted plan view of a cut-glass vessel, showing my design; and Fig. 2 is 15 a sectional side elevation of the same.

The leading feature of the design consists in the lapidary center A—that is, a center 20 cut with facets in imitation of a finished diamond—rising on a plane-surfaced polygonal figure B.

A minor feature of the design consists in the grouped parts A and B, arranged in the external angles of the two intersecting equilateral triangles C.

Another minor feature is the border around 25 the grouped parts A and B, the border appearing with alternately-arranged single fields D and double fields E.

Having thus fully described my invention, I claim as new and desire to secure by Letters 30 Patent—

The design for a cut-glass vessel, as herein shown and described.

In testimony whereof I have signed my name to this specification in the presence of 35 two subscribing witnesses.

THOMAS B. CLARK.
